CLAIM

The ornamental design for an unmanned robotic vehicle, as shown and described.

DESCRIPTION

FIG. 1 is a top right front perspective view of an unmanned robotic vehicle, showing my new design;

FIG. 2 is a top left rear perspective view thereof;

FIG. 3 is a front elevational view thereof;

FIG. 4 is a right side elevational view thereof;

FIG. 5 is a rear devotional view thereof;

FIG. 6 is a right side elevational view thereof; and,

FIG. 7 is a top plan view thereof.

The broken lines in the drawings represent portions of the unmanned robotic vehicle that form no part of the claimed design.
